[57] CLAIM

The ornamental design for a gasket, as shown and described.

DESCRIPTION

FIG. 1 is a perspective view of a gasket showing our new design.

FIG. 2 is a top plan view thereof;

FIG. 3 is a bottom plan view thereof;

FIG. 4 is a side elevational view thereof; the other sides being the same as the side shown; and

FIG. 5 is an enlarged cross sectional view taken on line 5—5 of FIG. 2.

FIG. 1
